Patented Aug. 4, 1959

185,802

HAND PUPPET

Hilda Lou Cohen, Fort Worth, Tex.

Application March 19, 1958, Serial No. 50,095

Term of patent 14 years

(Cl. D34—2)

Fig. 3

Fig. 1

Fig. 4

Fig. 2

Fig. 1 is a perspective view of a hand puppet showing my new design;

Fig. 2 is another perspective view thereof;

Fig. 3 is another perspective view thereof; and

Fig. 4 is a perspective rear view.

The specific wearing apparel of the puppet shown in dotted lines is for illustrative purposes only.

I claim:

The ornamental design for a hand puppet, as shown and described.
